UNITED STATES PATENT OFFICE.

EDWARD J. PENNINGTON, OF CLEVELAND, OHIO.

LAUNCHING AND TRIAL APPARATUS FOR AERIAL CRAFT.

No. 893,647.

Specification of Letters Patent.

Patented July 21, 1908.

Application filed January 22, 1904. Serial No. 190,179.

To all whom it may concern:

Be it known that I, EDWARD J. PENNINGTON, a citizen of the United States, residing at Cleveland, in the county of Cuyahoga and State of Ohio, have invented certain new and useful Improvements in Launching and Trial Apparatus for Aerial Craft, of which the following is a specification, reference being had to the accompanying drawings, forming part thereof.

My invention is intended, more especially, for use with aerial craft not provided with gas or buoyancy chambers and which are dependent for flotation in the atmosphere upon the operation of aeroplanes, wings or other sustaining media. It is obvious that difficulties and grave dangers must attend the launching, and the experimental and other trials of such vessels, inasmuch as their operativeness cannot be safely determined until they are elevated from the earth or fairly launched, and that any accident to the machinery, or imperfect construction in the vessel itself, or other causes, may result in the destruction of the vessel and loss of life. Therefore, I have devised means whereby the vessel may be put in motion, and its operativeness and that of its machinery fully proved, while protected from injury or destruction in the event of any failure in its machinery or structural parts.

My invention relates, first, to a structure from which the vessel may be suspended at a desired distance from the earth and its elevating and propelling machinery put in motion, so that the correctness of the principles of construction involved, and the efficiency of its machinery, may be fully tested before the vessel is released for flight.

My invention also relates to means whereby, during the experimental tests of the vessel, the operator or navigator may determine whether the vessel is actually suspended, or whether it is self-supporting in whole or in part due to the action of its machinery, so that he may know when it is advisable to release the vessel and allow it to begin its voyage.

My invention further relates to means whereby the vessel may be lifted to and released from the point of suspension.

In the accompanying drawing, Figure 1 is a view in elevation illustrating my invention. Fig. 2 is a plan indicating the course taken by the vessel in motion while suspended. Figs. 3 and 4 show details.

Similar numerals of reference indicate similar parts in the respective figures.

1—1 are towers or masts which may be of any approved construction or design and which may be braced by means of wire ropes or guys 2—2 or otherwise. The space between the towers or masts 1 is occupied by a suitable support 3, preferably a stout wire rope, or it may be a trussed structure or otherwise adapted to the purpose.

4 is a central suspending device preferably furnished with a sheave or wheel 5.

6 may represent in a general way an aerial vessel which is suspended from the support 3 by a rope 7 which passes over the sheave or wheel 5 and may be led to one of the masts passing over a sheave 8 down to near the base of the mast, and there secured. Between the vessel 6 and the suspending rope 7 is inserted a device 9 in the nature of a scales or weighing medium.

The vessel 6 being ready for operation, whether experimental or otherwise, is lifted to the required height from the earth by drawing on the suspending rope 7, and maintained at the proper elevation. The weight of the vessel having been previously ascertained, it will be indicated upon the dial 12 of the weighing device 9; and when the vessel is stationary, or is actually suspended—*i. e.* not in whole or in part self-supporting, that weight will continue to be so indicated. The engine of the vessel having been started, the vessel will begin to move in a spiral track, describing lines as indicated in Fig. 2. A true circle will finally be described, and the vessel may now be kept in motion, moving around this circle until its operativeness and that of its machinery is satisfactorily established, when the vessel may be released by detaching it from the suspending rope 7. In order to permit such detachment, hooks 10, 11 or their equivalent, are provided, connecting, respectively, the rope 7 with the vessel; and to permit the lifting of the vessel to the required height for the testing purpose, the winding mechanism 12 is provided at the foot of a mast. By means of the weighing device the operator will be enabled to determine whether the vessel, when attached to the rope 7 and in motion, is exerting its full weight upon the rope or is being gradually lifted by its own machinery, a lessening of the weight originally indicated upon the dial 12—that being the weight of the loaded and stationary vessel—informing the operator

that the craft is becoming self-supporting or the extent to which it is sustained by the rope.

My invention is capable of variation in arrangement and construction, but it is essential that the vessel shall, during experimental tests while in motion, be suspended from a fixed object.

It is not essential to my invention that there should be used the weighing and registering device serving to indicate the extent to which the moving vessel is self-supporting, although I prefer to use the same in connection with the vessel and its supporting devices.

It will be understood that there may be more than one connection made between the suspending rope and the vessel, that being determined by the size and construction of the latter. The structure herein described may also be used for anchoring the vessel during experimental trial, or at the end of a trip, all that is necessary to this end being that it shall be steered to a position enabling the suspending rope or ropes to be reattached to said vessel.

Having thus described my invention, I claim:—

1. The combination of a fixed supporting structure, a self-propelling aerial vessel, means for suspending, elevating and lowering said vessel, means for weighing and indicating the decreased weight of the moving vessel as it becomes self-supporting, and de-

taching means, said weighing and detaching means being interposed between the suspending means and the vessel and adjacent to the latter so to be capable of observation and operation by the navigator, substantially as set forth.

2. The combination of a pair of towers or masts erected a suitable distance apart, a support connecting the tops of said towers or masts, a suspending device centrally attached to said support and carrying a sheave or wheel, a suspending rope extending from the foot of one of said towers or masts upward and over said sheave, a self-propelling aerial vessel supported by said suspending rope, a winding mechanism employed with said suspending rope for raising and lowering said vessel, weighing means inserted between the suspending rope and said vessel and adjacent thereto, and detaching means also inserted between the suspending rope and said vessel and adjacent thereto, whereby the navigator may observe the indication of dead weight and the diminution of weight as the vessel becomes self-supporting and he may detach it from the suspending means for aerial flight, substantially as set forth.

In testimony whereof I hereunto set my hand.

EDWARD J. PENNINGTON.
